ELECTROSTATIC DEVICE FOR SOUND REPRODUCTION

Application filed October 5, 1928. Serial No. 310,474.

The present invention relates to electrostatic devices for sound reproduction and production.

Among the objects of the invention is to provide a novel electro-static sound producer and reproducer having conductors and dielectric having the properties or characteristics of permitting the rapid dissipation or discharge of static charges, especially those tending to residually remain or lag in the material of the dielectric. In the illustrative embodiment, the dielectric may be of sheet material stretched over the surface of a metal plate having openings, and carrying on its opposite face a flexible metal member or coating, such as gold or silver leaf, aluminum foil and other like and similar conductors, or even a coating of metal suitably applied thereto. The dielectric is one that has a slight amount of conductivity or one that is not a perfect insulator or dielectric, so that dissipation or draining off of static charges, particularly that tending to remain residually or to lag in the material of the dielectric, may be rapidly effected.

I have discovered that by using a dielectric which is not a perfect insulator but has a slight amount of conductivity or leakage, the static charges change polarity or potential levels without lag. The slight amount of conductivity in the dielectric is not such as to affect the charge in the main but offers an efficient way for the rapid discharge, draining off or dissipation of the part of the charge that would normally tend to residually remain or lag in the dielectric material. As examples of such dielectric, are rubberized nainsook, rubberized silk, fabrics impregnated with insulating material, low grade rubber, gutta percha, vulcanized cloth, vulcanite, fabrics such as cotton, silk, linen and the like, resinized with resinous compounds, such as synthetic resins and other like and similar materials.

Other objects, capabilities, advantages and features are comprehended by the invention as will later appear and are inherently possessed thereby.

Referring to the drawings, Fig. 1 is a view in elevation of a sound producer or reproducer constructed in accordance with the invention, with parts shown broken away; and Fig. 2 is a fragmentary sectional view on an enlarged scale.

Referring more in detail to the drawings, the embodiment selected to illustrate the invention is shown with a base 1, carrying a frame 2 suitably supporting a plate 3 of metal and having a number of openings 4. The plate is preferably made with a number of depressions or troughs with inclined or deflected surface areas or regions between the main surface 5 of the plate and the openings 4, such surfaces diverging slightly from the plane of the surface 5 as clearly shown in Fig. 2. Stretched to extend over the surface 5 of the plate is a dielectric 6 having the characteristics above described. On the opposite side of the dielectric is provided a flexible metal surface or member 7 which may be foil or leaf of metal or even a coating applied to the surface of the dielectric by spraying or the like.

The dielectrics may be of the materials above mentioned and having the characteristics described. In operation, the plate 3 and the flexible metal member 7 are connected to opposite sides of a circuit from which sound may be reproduced from electrical energy. Due to either opposite polarities of the charges or difference in potential levels of the charges on these metal members and as induced into the material or the surface of the dielectric 6, the dielectric will vibrate to produce sound. While I am not ready to state what is the theory of the action or effects of the static charges, it appears that the static charges are present upon the surface of the dielectric or in the material thereof, and

when the charges change either in polarity or potential levels, dissipation or discharge of the charges will in the main be effected rapidly, but under normal conditions, if the 5 dielectric be a pure or absolute insulator, there is generally a residual charge that tends to lag or to be slowly dissipated from the dielectric material. By use of the material herein disclosed, a slight amount of conductivity is present, which will efficiently permit 10 the rapid leaking off or drainage of the residual or lagging charges. In the case of using an impregnated fabric, it appears that the fibers or the threads of the fabric have 15 sufficient conductivity characteristics to effect this result, yet not being such as to in any way materially effect the main charge. I have found from experiments that the changes in the charges are effected far more 20 rapidly than has heretofore been possible with such dielectrics as high grade sheet rubber or the like, and that there is a clearer tone production effected. The noise usually parasitic upon the sound usually coming from 25 a sound reproducer, is remarkably absent from this type of sound producer.

While I have herein described and upon the drawings shown an illustrative embodiment of the invention, it is to be understood that the invention is not limited thereto but 30 may comprehend other constructions, details, arrangements of parts and features without departing from the spirit thereof.

Having thus disclosed the invention, I 35 claim:

1. An electro-static sound reproducer comprising conductors and an interposed dielectric having a slight amount of conductivity for the rapid dissipation of static charges 40 tending to remain residually in the dielectric.

2. An electro-static sound reproducer comprising conductors and an interposed insulation of impregnated substance having a slight amount of conductivity for the rapid dissipation 45 of static charges tending to remain residually in the insulation.

3. An electro-static sound reproducer comprising conductors and an interposed dielectric having a resistivity slightly less than that 50 of a perfect dielectric for rapidly discharging static charges tending to remain residually in the dielectric.

4. An electro-static sound reproducer comprising a metal plate having openings therein, a flexible dielectric diaphragm juxtaposed 55 to a face of the plate, and a flexible metallic member on the opposite surface of said diaphragm, said diaphragm having a resistivity slightly less than perfect resistivity whereby 60 lag in static discharges may be reduced to a minimum.

5. An electro-static sound reproducer comprising a metal plate having openings therein, a flexible dielectric diaphragm stretched 65 over a face of the plate, and a flexible metallic

member on the opposite surface of said diaphragm, said diaphragm having a slight amount of conductivity for substantially eliminating lag in static discharges.

6. An electrostatic translating device comprising a fixed element, a movable element 70 and a slightly-conducting substance interposed therebetween.

7. An electrostatic translating device comprising a plurality of elements separated by 75 a slightly-conducting substance.

In witness whereof, I hereunto subscribe my name to this specification.

COLIN KYLE.
